Primary Examiner — Karen E Eldridge Powers(74) *Attorney, Agent, or Firm* — Baker & Hostetler LLP(57) **CLAIM**

The ornamental design for a two-finger glove, as shown and described.

DESCRIPTION

FIG. 1 is a front view of a two-finger glove in accordance with the invention;

FIG. 2 is a rear view thereof; and,

FIG. 3 is a perspective view thereof.

The hand shown in broken lines illustrates the environment in which the design is used and forms no part of the claim.
